UNITED STATES PATENT OFFICE.

FREDERIC W. HILLARD, OF TOTTENVILLE, NEW YORK, ASSIGNOR TO THE ELLIOTT & HATCH BOOK TYPEWRITER COMPANY, A CORPORATION OF NEW YORK.

TYPE-WRITER.

SPECIFICATION forming part of Letters Patent No. 685,762, dated November 5, 1901.

Application filed January 13, 1899. Serial No. 702,054. (No model.)

To all whom it may concern:

Be it known that I, FREDERIC W. HILLARD, a resident of Tottenville, county of Richmond, and city and State of New York, ⁵ have invented certain new and useful Improvements in Type-Writers, of which the following is a specification.

My invention is an improvement in type-writing machines, which relates to a simple ¹⁰ and efficient means for shifting the type-heads upon the type-bars in order to effect the printing of a plurality of type with the same type-bar. This improvement is designed more especially for use on machines ¹⁵ adapted for writing on bound books. On such machines the paper is placed upon a flat platen or printing-surface in contradistinction to the cylindrical platen of the ordinary commercial-letter writer. The invention is, ²⁰ however, adapted to machines whether the platen is provided with a flat printing-surface or a curved one.

My invention also comprises the various details of construction herein shown and described.

In the accompanying drawings, which form a part of this specification, Figure 1 is a sectional side elevation of the machine, showing some of the type-bars and type-heads and the ³⁰ mechanism for shifting the type-heads on the type-bars from one printing-base to another. Fig. 2 is a detail of a type-head of Fig. 1. Fig. 3 shows a modified type-bar with its type-head and several other parts which are operatively connected therewith. Fig. 4 is a detail of the type-head of Fig. 3. Fig. 5 is a sectional detail of a portion of the type-bar and of the pivot of Fig. 3. Fig. 6 is a side view of the parts shown in Fig. 5.

The carriage A is mounted for lateral movement upon frame B and is supported thereon by rollers W W at the front and at the rear, which rest upon guide-rails g g, fixed to frame B. The type-bars T are pivotally ⁴⁰ mounted on hangers T', so that they can be moved from the buffer-ring b to the platen for printing. The hangers T' are arranged concentrically around the circular opening in the carriage A, so that the type will all ⁴⁵ print at a common center. I have only shown two of the type-bars, one at the front and one

at the rear of the machine; but I wish to have it understood that there is a circular opening in the carriage and that the type-bars extend entirely around this circle. The type-heads ⁵⁵ H are pivotally connected to the type-bars by the type-head screws C. Each type-head comprises two type, an upper-case type u and a lower-case type l. Both of these type are formed integral with the type-head, and each ⁶⁰ of them is provided with a shank u' and l', respectively, which connect them with the main body of the type-head. Some of the functions of these shanks u' and l' are to correct any imperfection in the positioning of ⁶⁵ the two type u and l relatively to one another upon the type-heads. The shanks are so made that they can be bent and twisted so as to establish the proper distance between the two type, and they can be cut with pliers in order ⁷⁰ to throw the type upon their feet—that is to say, to cause it to strike the paper evenly. The type-heads are controlled in both printing positions on the type-bars by means of type-head spring S, the type-head being provided with a tapered projection i and the type-head spring being provided with a mounted indentation j for engagement therewith. The projection i and the indentation j are so positioned relatively one to the other that the ⁷⁵ point of the projection i shifts across the point of indentation j when the type-head is shifted from one printing position to another, and the inclined faces on both sides of the indentation j upon spring S engage with the corresponding inclined faces on the sides of the projection i to control the type-head on the type-bar in each printing position. The type-heads are each provided with the banking-faces m and n, and each type-bar is provided ⁸⁰ with corresponding banking-stops m' and n', which engage with the banking-faces m and n and positively limit the throw of the type-heads upon the type-bars in either direction.

The method in which I construct the modified type-bar T of Fig. 3 is as follows: I first punch the bar out of sheet metal. Then I force the metal comprising the banking-stops m' and n' out of the body of the type-bar, forcing this metal half-way through, so that it ⁹⁵ may comprise the banking-stops m' and n', but only partially through, so it still remains

an integral part of the type-bar. I then punch a hole through the pivotal portion of the type-bar and a hole through the lower extremity of the bar to receive one end of the wire connecting the type-bar with the corresponding key-lever. Through the pivotal hole I insert a short piece of wire and rivet this wire on each side of the hole. This forms the body *d*, of sufficient thickness to securely hold pivot *s* of the type-bar. The type-bars are connected with the key-levers *V* by means of the connecting-wires *v v*, and at the opposite end of the key-levers the finger-keys *K K* are provided in the usual manner. The type-bars are normally held in a perpendicular position, with the type-heads resting in buffer *b*, by means of key-lever springs *V' V'*. The operation of my type-bars and type-heads is as follows: Mechanism is provided for shifting the type-heads from the lower-case position to the upper-case position on type-bars, which I will now describe. Shift-key lever *R* is connected by means of shift-key-connecting wire *L* to the rocker-shaft arm *M*, which is rigidly fastened to one end of the rocker-shaft *N*. To the opposite end of the rocker-shaft *N* the rocker-shaft arm *O* is rigidly fastened and operatively connected by a pin (not shown) with disk plunger-rod *P*. The disk plunger-rod is normally held in a raised position by means of shift-spring *Q*, thereby holding the tripper-disk *D* normally in the raised position shown in dotted line in Fig. 1. Fig. 1 shows the parts of the machine with shift-key lever *R* depressed and the disk *D* lowered into operative position to effect the shifting of the type-head from the lower-case printing position to the upper-case printing position. The tripping end *a* is of such length from the pivotal center of the type-head that when engaged by disk *D* upon the depression of shift-key lever *R* it will force the type-head to be swung on its pivot far enough for the point of the projection *i* to move across the point of indentation *j*. After the type-head has been swung thus far the pressure of the spring *S* against the upper inclined face of the projection *i* will complete the movement of the type-head until the banking-face *m* engages the banking-stop *m'*, which limits the movement of the type-head on the type-bar. When the type-bar is in position for printing with the upper-case type, the tripping end *a* swings with the type-bar free of disk *D*. Therefore when the type-head is in the upper-case printing position upon the release of the type-key *K* the type-bar will swing up past disk *D* until the type-head engages with buffer *b*, and then the pressure of the tripping end *a* against buffer *b* shifts the type-head back to lower-case printing position, with the banking-face *n* in engagement with banking-stop *n'*. When the shift-key lever *R* and the tripper-disk *D* are in their raised positions, the type-heads are not shifted on the type-bar when the printing-keys *K K* are operated. The type-heads remain at all times

while in the buffer *b* in the lower-case printing position; but when the shift-key lever *R* is depressed, together with disk *D*, each type-head will be shifted by contact of tripping end *a* with disk *D* from lower-case printing position to upper-case printing position during the depression of the printing-key, and will then be returned to lower-case printing position upon the release of the key by contact of tripper end *a* with buffer *b*.

I do not in this application make any claim to the above-described tripping and controlling mechanism for the type-head except in their combination with the integral type-head herein described, as such tripping and controlling mechanism form the subject-matter of and are claimed in my application filed May 25, 1897, serially numbered 638,007, renewed July 31, 1900, as Serial No. 25,454, and my application filed as a division thereof on August 4, 1900, Serial No. 25,928.

Having thus described my invention, what I claim, and desire to secure by Letters Patent, is—

1. The combination in a type-writer of a movable type-bar, and a type-head pivotally mounted thereon and provided with a plurality of type adapted to be brought into printing position by the pivotal movement of the type-head, the type-head and types being connected by shanks, the type-head, types and shanks being integral with each other and formed of pliable material, whereby the types may be adjusted in their relative position upon the type-head, substantially as described.

2. In a type-writer, the combination of a movable type-bar, a type-head pivotally mounted thereon and provided with a plurality of type, which are formed integral with the type-head, a tripper movable from and into the path of the type-head to shift the type-head on the type-bar from one printing position to another printing position during the printing stroke of the type-bar, and a fixed buffer for reshifting the type-head to its first printing position on the type-bar upon the return of the type-bar to normal position, substantially as described.

3. In a type-writer, the combination of a movable type-bar, a type-head pivotally mounted thereon and provided with a plurality of type which are formed integral with the type-head, a tripper movable from and into the path of the type-head to shift the type-head on the type-bar from one printing position to another printing position during the printing stroke of the type-bar, and a fixed buffer for reshifting the type-head to its first printing position on the type-bar upon the return of the type-bar to normal position and for limiting the return movement of the type-bar, substantially as described.

4. In a type-writer, the combination of a type-bar, a type-head pivotally mounted thereon and provided with a plurality of type, means for shifting the type-head on the type-

bar and for controlling it in a plurality of printing positions, whereby each type is successively brought to the printing-point on the type-bar, said type being formed integral with the type-head, substantially as described.

5. In a type-writer, the combination of a type-bar, a type-head pivotally mounted thereon and provided with a plurality of type, means for shifting the type-head on the type-bar and for controlling it in a plurality of printing positions, whereby each type is successively brought to the printing-point on the type-bar, said type being formed upon and integral with the outer ends of radiating projections integral with the type-head, substantially as described.

10 15 6. In a type-writer, the combination of a

type-bar, a sheet-metal type-head pivotally mounted thereon and provided with a plurality of type, means for shifting the type-head on the type-bar for controlling it in a plurality of printing positions, whereby each type is successively brought to the printing-point on the type-bar, said type being formed upon and integral with the outer ends of radiating projections integral with the type-head, substantially as described.

20 25 Signed by me in New York city this 11th day of January, 1899.

FREDERIC W. HILLARD.
